By Burton W. Kelly, Atty.

UNITED STATES PATENT OFFICE.

GEORGE BROWNING, OF CHICAGO, ILLINOIS.

SAFETY-RAZOR.

1,346,294.

Specification of Letters Patent.

Patented July 13, 1920.

Application filed September 27, 1918. Serial No. 255,968.

To all whom it may concern:

Be it known that I, GEORGE BROWNING, a subject of the King of England, residing at Chicago, in the county of Cook and State 5 of Illinois, have invented certain new and useful Improvements in Safety-Razors, of which the following is a description.

My invention relates to that general class of devices known as razors and especially 10 to the class of razors known as safety razors.

The object of my invention is to produce a simple, convenient and highly efficient device of the kind described which may be provided with means for especially adjusting 15 the device for the particular service required and provided with means for its safe, convenient and rapid manipulation.

To this end my invention consists in the novel construction, arrangement and combination 20 of parts herein shown and described, and more particularly pointed out in the claims.

In the accompanying drawings wherein like or similar reference characters indicate 25 like or corresponding parts;

Figure 1 is a side elevation of my device.

Fig. 2 is a front elevation of the same.

Fig. 3 is a section taken substantially on line 3—3 of Fig. 2.

Fig. 4 is an end view of my improved 30 razor.

Fig. 5 is a section taken substantially on line 5—5 of Fig. 1.

Fig. 6 is an enlarged section taken substantially on line 6—6 of Fig. 4.

Fig. 7 is a plan view of a cutting blade for my improved razor.

In the form shown my device comprises a handle 1 formed of any suitable material 40 provided with a transverse head 2 at one end rigidly attached thereto and positioned at a suitable angle to the handle to provide for the proper application of the blade to the face. The head 2 is preferably of suitable length to provide a backing for a blade-holder mounted thereon and is also preferably provided with a guard for the cutting edge comprising a plurality of fingers 3 each 45 preferably projecting into the cutting plane of the blade and extending laterally beyond the cutting edge of the blade 4 in position to prevent accidental injury from the edge 50 of the blade. Any convenient means may be

provided for mounting the blade 4 in suitable position upon the head 2 and providing 55 for longitudinally moving the same when my improved razor is in service. As shown a blade-holder 5 is mounted upon the head 2 comprising a base 6 one side of which is suitably formed to receive and provide a 60 suitable bearing for a cutting blade while the opposite side is formed to fit upon and bear against the head 2 and having a pair of laterally extending lugs or buttons 7 one near each end of the base, each rigidly attached thereto and each extending through a slot 8 in the head 2 to hold the blade-holder 65 in position upon the head. The walls of the slots 8 are each substantially parallel to the margin of the head 2 and the buttons 7 are 70 provided with suitably enlarged heads adapted to engage the underside of the head 2 to retain the part 6 in position upon the head, yet permit of its free longitudinal movement thereon.

Suitable means are also provided to secure the blade 4 in position upon the base 6. As shown a cap 10 is provided extending longitudinally of the head 2 with one end pivotally attached to the base 6 as at 18 and 80 the opposite end provided with a resilient tongue or latch 11 adapted to coöperate with the base to resiliently maintain the cap 10 in position and hold the blade firmly upon the base 6.

In the preferred construction also suitable means are provided to positively control the transverse position of the blade upon the base. As shown a pair of pins or studs 9 are provided in the blade-holder 5 each 90 having a head 19 at its upper end projecting above the upper surface of the base 6 and adapted to engage suitable openings 20 and 21 respectively in the blade 4. In the preferred construction each stud 9 extends 95 through a central opening in the lugs or buttons 7 with a laterally bent portion or handle 22 at the lower end of the lug adapted to resiliently engage the slots or recesses 23 upon the under side or head of each button 100 to control the position of the stud, the head 19 of which is preferably formed eccentric to the central axis of the stud so that by rotating the stud the blade 4 may be moved transversely of the head. For this purpose the 105 opening 20 in the blade 4 is formed to ac-

curately fit the head 19 while the opening 21 is of substantially the same size transversely but slotted longitudinally of the blade to provide for the longitudinal movement between the studs when adjusting the same. The opening 20 is adapted to engage its particular head 19 to control the longitudinal position of the blade upon the head as well as the transverse position of one end 10 of the same while the opening 21 coöperates with its head 19 to control the transverse position of the opposite end of the blade.

Suitable means are also provided for raising the blade from the base 6 after the cap 15 10 has been released. As shown the handle 1 is provided with a neck or reduced portion 24 adjacent its connection to the head 2 and a finger piece 25 is provided having an opening adapted to loosely fit the neck 24 to retain the finger piece in position and a part 20 or arm 26 at its opposite end at substantially right angles to the body portion of the finger piece extending into an opening 27 in the head beneath the blade 4 adjacent its cutting edge. A slotted opening 28 is provided in the base 6 arranged to register with the opening 27 and permit the part 26 to be moved upward and engage the blade to raise the same from the base 6 to facilitate its removal when desired.

Any suitable means may be provided for imparting longitudinal reciprocating motion to the blade-holder 5. In the preferred construction an arm 12 is provided at each 35 end of the head 2 projecting beyond the blade-holder 5 substantially in line with the handle 1 but at the opposite side of the head and a roller 14 is rotatably mounted between the arms 12 and arranged to freely 40 rotate on suitable bearings formed in said arms. A portion 15 at each end of the roller is formed to operate as a cam preferably having two projections substantially parallel with the axis of the roller at each end 45 thereof. The portions 15 are formed to co-operate with suitable arms 16-16 formed upon the rear of the base or part 6 and adapted to engage the respective parts 15 at the opposite ends of the roller to move 50 the blade-holder longitudinally when the roller is rotated and to accurately control the longitudinal position of the blade-holder upon the head 2.

The several parts are so formed that when 55 the roller 14 is in contact with a surface the cutting edge of the blade 4 will be at the most advantageous angle to said surface for shaving the surface, thereby providing a guide for accurately controlling the angle 60 at which the blade is presented to the surface to be operated upon. The bent portions or arms 22 are adjusted to bring the blade to the desired transverse position upon the head to operate as desired upon the surface to be shaved.

When in service the roller 14 contacts with the surface after the blade has passed thus removing any lather or hair previously upon the surface thus avoiding accumulations upon the roller and providing a comparatively clean surface for rotating the roller at each lateral movement of the blade in the shaving operation and the rotations of the rollers, the surface of which is preferably fluted or roughened slightly to insure 75 its proper engagement with the shaved surface, reciprocates the blade longitudinally thus securing the well known draw stroke in the cutting operation.

Having thus described my improvement 80 it is obvious that various immaterial modifications may be made in my device without departing from the spirit of my invention, hence I do not wish to be understood as limiting myself to the exact form or construction shown.

What I claim as new and desire to secure by Letters Patent is:

1. A device of the kind described, comprising a handle, a supporting guard blade 90 fixedly secured thereto, provided with means for operatively engaging a razor blade placed thereon, a coöperating razor blade therefor, a latch piece pivotally secured to one end of the guard and extended to lie 95 above the guard and engage the other end thereof to maintain the blade in position on the guard, in combination with a lever extending transverse the guard, pivotally supported between its ends in a central position 100 on the device, with one end extending to a point near the front of the guard and thence bent to extend through an opening therein to contact with the blade, and its other end extended for operative purposes.

2. A device of the kind described, comprising a handle, a supporting guard blade fixedly secured to the handle, provided with projecting pins on its upper surface for engagement with the razor blade, a razor blade 110 provided with coöperating openings to engage the pins, a latch piece pivotally secured to one end of the guard and extended to lie above the guard and engage the other end thereof to maintain the blade in position between the two, in combination with a lever extending transverse the guard, pivotally supported between its ends in a central position on the device, with one end 115 extending to a point near the front of the guard and thence bent to extend through an opening therein to contact with the blade, and its other end extended for operative purposes.

3. A device of the kind described, comprising a handle, a supporting blade fixedly secured to the handle, a coöperating razor blade and means for operatively securing the blade on the guard, in combination with a lever extended transverse the guard, piv- 125 130

otally supported between its ends in a central position on the device, with one end extending to a point near the front of the guard and thence bent to extend through
5 an opening therein, in contact with the blade, and its other end extended for operative purposes:

In testimony whereof I have hereunto signed my name in the presence of two subscribing witnesses.

GEORGE BROWNING.
